UNITED STATES PATENT OFFICE.

EDWARD J. COUGHLIN, OF PASSAIC, NEW JERSEY, ASSIGNOR TO NEW YORK BELTING & PACKING COMPANY, OF NEW YORK, N. Y., A CORPORATION OF NEW YORK.

DESIGN FOR RUBBER HOSE.

46,944.

Specification for Design.

Patented Feb. 16, 1915.

Application filed October 30, 1912. Serial No. 728,673. Term of patent 14 years.

To all whom it may concern:

Be it known that I, EDWARD J. COUGHLIN, a citizen of the United States, residing in the city of Passaic, county of Passaic, State of New Jersey, have invented a new, original and ornamental Design for Rubber Hose, of which the following is a specification, reference being had to the accompanying drawing, forming a part thereof, in which—

Figure 1 is a side elevation of a section

of hose; and Fig. 2 is a cross-section on the line 2—2 of Fig. 1.

I claim:

The ornamental design for rubber hose as shown.

EDWARD J. COUGHLIN.
